Primary Examiner—Celia A. Murphy*(74) Attorney, Agent, or Firm*—St. Onge Steward Johnston & Reens LLC(57) **CLAIM**

I claim the ornamental design for an outsole for a shoe, as shown and described.

DESCRIPTION

FIG. 1 is a bottom view of an outsole for a shoe showing my new design;

FIG. 2 is a right side view thereof;

FIG. 3 is a left side view thereof;

FIG. 4 is a front view thereof;

FIG. 5 is a back view thereof;

FIG. 6 is an enlarged perspective view of the area labeled "6" in FIG. 1; and,

FIG. 7 is a cross sectional view taken along line 7—7 shown in FIG. 6.

The broken line showing an oval shape in the arch area of FIG. 1 represents the boundary of the design, with neither the line itself, nor the area within it forming any part of the claim.
